(57) **CLAIM**

The ornamental design for a footwear, as shown and described.

DESCRIPTION

FIG. 1 is front, top and left side perspective view of a footwear showing our new design;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof;

FIG. 7 is a bottom plan view thereof; and,

FIG. 8 is a bottom and left side perspective view thereof.

The dot-dashed broken lines in FIGS. 1-5, 7 and 8 represent the boundaries of the claim and form no part of the claimed design. The broken lines in FIGS. 1-8 represent portions of the footwear that form no part of the claimed design.

1 Claim, 8 Drawing Sheets
